APPARATUS FOR REMOVING A COVERING
FROM A COREHarlow F. Gaylord, La Grange, Ill., assignor to
Western Electric Company, Incorporated, New
York, N. Y., a corporation of New YorkApplication December 10, 1930
Serial No. 501,315

5 Claims. (Cl. 81—9.51)

This invention relates to an apparatus for removing a covering from a core, and more particularly to an apparatus for removing sheath from a lead covered cable.

5 An object of this invention is to provide a simple, efficient, and practical apparatus for removing a sheath from lead covered cable without preliminarily slitting the sheath.

In one embodiment of the invention a pair of pressing rollers are provided for flattening a lead covered cable, for example, a telephone cable, guided therebetween, and simultaneously advancing the flattened cable between guides to oppositely disposed rotatable cutters. Positioned immediately adjacent the points of slitting are deflecting members spaced sufficiently to allow the passage of the cable therebetween and having their deflecting surfaces of such curvature to deflect the slit portions of the sheath away from the core and between advancing rollers which aid in advancing the cable and continue the advancement thereof after the cable has passed from between the pressing rollers. Guides positioned in advance of the pressing rollers, the pressing rollers, the guides between the pressing rollers and the cutters, the cutters, the deflecting members and the advancing rollers are all adjustable to accommodate cables of various sizes.

30 The invention will be more fully understood from the following descriptions, taken in connection with the appended drawings in which,

Fig. 1 is a side elevational view of the apparatus, portions thereof being broken away;

35 Fig. 2 is a top plan view of the apparatus; Fig. 3 is a vertical sectional view taken along 3—3 of Fig. 1;

Fig. 4 is a vertical sectional view taken along the line 4—4 of Fig. 1;

40 Fig. 5 is a schematic illustration of the operative connections of the various shafts with the power means;

Fig. 6 is a fragmentary perspective view of a portion of the apparatus, and

45 Fig. 7 is a horizontal sectional view taken just above the slitting knives and the deflecting members.

Referring now to the drawings wherein like reference numerals designate similar parts throughout the various views, a supporting base 10 has mounted thereupon vertically extending supporting frames 11 and 12 disposed in a parallel spaced relation and having connecting plates or members 13 and 14 extending across the upper edges thereof and rigidly secured

thereto. Adjacent the entrance end of the passageway between the vertically extending frame members 11 and 12 are resilient guides 15 and 16 held by bolts to the frames 11 and 12, respectively, at their outer ends, their inner ends being disposed adjacent adjusting screws 17 and 18 by the aid of which the positions of the guides 15 and 16, relative to each other, may be varied.

Positioned between the frames 11 and 12 near the inner ends of the guides 15 and 16 are pressing rollers 21 and 22 mounted upon shafts 23 and 24, respectively, and arranged to be rotated in opposite directions to flatten and simultaneously advance the cable guided therebetween by the guides 15 and 16. The shaft 23 is journaled in the frames 11 and 12 and has its ends extending outwardly therefrom for receiving sprockets 25 and 26 (Fig. 5) which are keyed in the end thereof adjacent the frame 11 and for receiving a sprocket 27 which is keyed to the end thereof adjacent the frame 12. A chain 28 passing over the sprocket 27 operatively connects the shaft 23 with a sprocket 29 of a power means (not shown). The shaft 24 is journaled in adjustable bearing blocks 32 movably disposed in guides in the frames 11 and 12, the ends of the shaft 24 extending outwardly from the bearing blocks. The bearing blocks 32 are supported by adjusting screws 33 extending through threaded apertures in the connecting plate 13 for varying the relative positions of the rollers 21 and 22. Mounted upon the outer end of the shaft 24 adjacent a frame 11 are sprockets 34 and 35, the sprocket 34 having a chain 36 thereupon which passes around a sprocket 37 mounted upon a shaft 38. The shaft 38 and a shaft 39 extend in parallel relation through the frame members 11 and 12, upon each side of the guides 15 and 16, and are operatively connected to each other by interengaging gears 40 and 41 mounted upon the ends of the shafts 38 and 39 respectively adjacent the frame 12.

Power is transmitted from the shaft 23 through the sprocket 25, a chain 42, a sprocket 43 on the shaft 39, from the shaft 39 through the gears 41 and 40 to the shaft 38, and from the shaft 38 through the sprocket 37, the chain 36 and the sprocket 34 to the shaft 24, thus rotating the roller 22 in a counterclockwise direction and at the same speed in which the roller 21 is rotated in a clockwise direction.

Positioned in front of the roller 21 is a stationary guide 50 serving as a platform to guide the cable when advanced. Above the stationary

guide 50 and disposed in parallel relation therewith is an adjustable guide 51 carried by a bracket 52 which is fixed to the guide blocks 32 so as to effect a simultaneous adjustment of the 5 guide 51 when the roller 22 is adjusted in position relative to the roller 21. At the sides of the guides 50 and 51 are tapered guide blocks 53 and 54, movably disposed in the frames 11 and 12 and connected together by an adjusting 10 screw 55 provided with right-hand and left-hand threads receivable in similarly threaded apertures in the guide blocks (Figs. 1, 2 and 4).

In advance of the guides 50 and 51 are rotatable slitting knives 56 (Figs. 1, 2 and 3), which 15 are equal in diameter and rotatably carried by adjustable supports 57, connected together by an adjustable screw 58 provided with right-hand and left-hand threads and positioned in similarly threaded apertures in the supports 57 so 20 as to move the supports toward or away from each other during the rotation of the adjusting screw. The adjustable supports 57 have outwardly extending projections 59, which are receivable in cutaway portions in the frames 11 25 and 12 to allow the adjustable supports to be moved toward or away from each other, yet holding the slitting knives 56 in any desired position.

Adjustable deflecting members 62, having outwardly flared surfaces 63 and 64, are movably disposed in cutaway portions 65 of the frames 11 and 12 and are arranged to be moved relative to each other by adjusting screws 66, carried by the frames 11 and 12 and having their 30 inner threaded ends receivable in threaded apertures of the deflecting members. The narrow inner portions of the deflecting members 62 have arcuate shaped slots in the inner walls thereof partially conforming to the slitting knives 56 and 35 terminating immediately adjacent the slitting positions to immediately move the slit portions of the sheath away from the core.

At the forward ends of the deflecting surfaces 63 and 64 are positioned advancing rollers 40 70, 71, 72 and 73, the advancing rollers 70 and 71 being positioned to receive the upper portion of the sheath, while the rollers 72 and 73 are positioned to receive the lower portion 45 of the sheath. The advancing rollers 70, 71, 72 and 73 are mounted upon shafts 74, 75, 76 and 77, respectively, the ends of the shafts 75 and 77 being journaled in the frames 11 and 12, while the ends of the shafts 74 and 76 are journaled in bearing blocks 78 and 79, respectively. The position of the roller 70 relative to the roller 71 may be varied by movement of 50 adjusting screws 83, which extend through threaded apertures in the connecting plate 14, and the relative positions of the rollers 72 and 73 may be varied by movement of adjusting screws 84. The operative connection of the 55 shafts 74, 75, 76 and 77 with the power means is illustrated in Fig. 5 wherein there is shown a chain 87 extending around the sprocket 26 of the shaft 23 and around a sprocket 88 of the shaft 77 and a chain 89 extending around a sprocket 90 of the shaft 77 and around a sprocket 91 of the shaft 75. A chain 92 extending 60 around the sprocket 35 of the shaft 24 and a sprocket 93 of the shaft 74 to rotate in a counterclockwise direction and due to a sprocket and chain connection 94 the shaft 76 is operatively connected to the shaft 74 and is rotated in the 65 same direction.

From the foregoing description of the various parts of the apparatus the operation thereof may be more clearly understood. When the apparatus is in operation, the pressing roller 21 rotating in a clockwise direction and the pressing roller 22 rotating in a counterclockwise direction a cable is fed between the shafts 38 and 39 and moved forwardly between the guides 15 and 16 and into engagement with the pressing rollers. The pressing rollers 21 and 22 will immediately grip the cable, compress it and simultaneously advance the cable in the flattened condition between the guides 50 and 51. The movement of the cable is continuous and at a predetermined speed so that when it passes from between the guides 50, 51, 53 and 54, it will pass between the slitting knives 56. Due to the flattened condition of the cable the sheath may be slit upon opposite sides by the knives 56, thus separating the sheath into two substantially flat strips which will immediately engage the deflected surfaces 63 and 64 of the deflecting members 62 and be guided so that the upper strip will be moved into engagement with the advancing rollers 70 and 71 and the lower strip 100 will be guided between the advancing rollers 72 and 73. The deflecting members 62 are spaced sufficiently to allow the core of the cable to pass therebetween to the exterior of the apparatus where it may be received by any suitable means (not shown). The strip portions of the sheath, when engaged by the advancing rollers 70, 71, 72 and 73, will be drawn out of the apparatus and the advancing rollers will continue to draw the cable between the knives 56 110 after the cable has passed completely from between the pressing rollers 21 and 22.

With this apparatus, a cable may be fed between the pressing rollers and advanced continuously past the slitting knives and through the apparatus without preliminarily threading the cable in the apparatus and without first slitting the sheath. The shafts 38 and 39, positioned one above and one below the guides 15 and 16, rotate in the proper directions to aid in advancing the cable to the pressing rollers 21 and 22. To condition the apparatus for receiving a different size cable the guides 15 and 16 are moved by the adjusting screws 17 and 18 to accommodate the cable. The pressing roller 22 is 125 also moved relative to the roller 21 by rotation of the adjusting screws 33 and at the same time movement is imparted to the adjustable guide 51 to properly position it relative to the guide 50. The guide blocks 53 and 54 are moved laterally to accommodate the different sized cable. Accurate guiding of the cable through the apparatus is essential and for this reason the guides 50 and 51 and the guides 53 and 54 are positioned as closely together as possible, thus 130 serving as means for retaining the compressed condition of the cable. The advancing rollers 70 and 72 may be moved relative to the rollers 71 and 73, respectively, to accommodate a sheath of different thickness.

While the invention has been described with reference to a specific embodiment thereof, it is understood that various modifications may be made therein without departing from the spirit and scope of the present invention.

What is claimed is:

1. In an apparatus for removing a sheath from a cable, a pair of pressing rolls, means for guiding a sheathed cable between said pressing rolls, means for adjusting one of said pressing

- rolls relative to the other whereby the rolls may flatten the cable guided therebetween, means for retaining the flattened condition of the cable, and means associating said retaining means with said adjustable means for effecting a simultaneous adjustment or said retaining means and said adjustable pressing roll. 50
2. In an apparatus for removing a sheath from a core, a pair of rolls for compressing the sheathed core and advancing the sheathed core to a slitting means, fixed surface means for receiving the compressed sheathed core from between said pressing rolls and for maintaining the compressed condition of the sheathed core 10 while being advanced to a slitting means, and means for slitting the sheath. 55
3. In an apparatus for removing a sheath from a core, a pair of rolls for compressing the sheath and advancing the sheathed core, stationary means for receiving the compressed sheathed core from between said pressing rolls and for maintaining the compressed condition of the sheathed core while being advanced to a slitting means, means for slitting the sheath, a deflecting member for deflecting the slit portions 20 of the sheath in transverse directions, and advancing rolls disposed adjacent the termination 25
- of said deflecting member for receiving and advancing the portions of the sheath. 30
4. In an apparatus for removing a sheath from a core, a pair of rolls for compressing and advancing the sheathed core, one of said rolls being movable relative to the other, means for slitting the sheath while advanced, guide members extending between said rolls and said slitting means for retaining the compressed condition of the sheathed core while being advanced, one of said guide members being movable with said movable roll, and means for moving said movable roll and said movable guide for varying the positions thereof relative to their respective members. 35
5. In an apparatus for removing a sheath from a core, a pair of rolls for compressing the sheathed core and advancing the sheathed core to a slitting means, flat retaining elements extending in parallel relationship and tangentially to the peripheries of said compressing rolls and spaced from each other a sufficient distance to retain the compressed condition of the sheathed core while being advanced to a slitting means, and means disposed adjacent said retaining elements for slitting the sheath. 40
